010-131. OR D 16,466 EX

DESIGN.

—o—

E. A. MARSH.

WATCH CROWN.

No. 16,466.

Patented Jan. 12, 1886.

UNITED STATES PATENT OFFICE.

EDWARD A. MARSH, OF NEWTON, MASSACHUSETTS.

DESIGN FOR A WATCH-CROWN.

SPECIFICATION forming part of Design No. 16,466, dated January 12, 1886.

Application filed November 16, 1886. Serial No. 183,052. Term of patent 14 years.

To all whom it may concern:

Be it known that I, EDWARD A. MARSH, of Newton, in the county of Middlesex and State of Massachusetts, have invented a new and 5 original Design for Watch-Crowns, of which the following is a specification.

The nature of my design is fully shown in the accompanying photographic illustration, forming a part of this specification, in which—

10 Figure 1 represents a side view of the winding-bar of a stem-winding watch and the crown or knob thereon, and Fig. 2 represents a top view of the crown.

Heretofore the crown on the winding-bar of 15 a stem-winding watch has been grooved to form ribs or projections extending across the periphery of the crown, each groove being in a plane parallel with the axis of the winding-bar. It has also been proposed to make said 20 grooves oblique to the plane of the axis of the winding-bar, each groove having a curved or ogee form, but in all cases the projections between the grooves have extended continuously across the crown.

The leading feature of my design is the 25 spherical form of the crown, on the central zone of which is a series of diamond-shaped pyramidal projections and a smooth plane on its top, as clearly shown in the accompanying photographic illustrations.

30 A watch-crown of the character mentioned is very ornamental in appearance, and presents to the eye a most pleasing effect.

I claim—

The design for a watch-crown of spherical 35 form, having diamond-shaped projections on its central zone and a smooth plane on its top, as described and shown.

In testimony whereof I have signed my name to this specification, in the presence of two 40 subscribing witnesses, this 14th day of November, 1885.

EDWARD A. MARSH.
